[57] **CLAIM**

The ornamental design for a support for salt for use in a water softener, as shown and described.

DESCRIPTION

FIG. 1 is a perspective view illustrating our new design; FIG. 2 is a bottom view thereof; FIG. 3 is a top plan view thereof; FIG. 4 is a side elevational view thereof, the opposite side is identical; and, FIG. 5 is a front elevational view thereof, the rear elevational view is identical.

The broken line drawing of a platform in FIG. 1 is for illustrative purposes only and forms no part of the claimed design.
